SALVAGING EQUIPMENT

Elisha L. Rader, Coeur d'Alene, Idaho

Application February 5, 1934, Serial No. 709,855

6 Claims. (Cl. 9—9)

My present invention relates to an improved salvaging equipment for marine vessels, liners, ships, etc. designed especially for the purpose of saving property from sunken or submerged ships.

In carrying out my invention I employ a salvaging tube or shaft as part of the equipment of the ship, which extends from the ship's strong-room or vault where valuable comparatively small articles are stored, to the top deck of the ship where the tube is provided with a trap closure or spring-opened twin-door or hatch that is closed and bolted at the inner side of the closure. A buoyant-container for the storage of valuables is housed in the salvaging tube within the ship's vault, where the container is readily accessible to authorized officers for storing valuables during the ship's passage, and from which the valuables may be withdrawn at the end of the passage.

Means are provided whereby the buoyant container may be floated from the salvaging tube to the water's surface when the ship is sunk, as in the event of a wreck, and thereafter the buoyant container performs the functions of a signal buoy in addition to its functions as a salvaging appliance, for acquainting a rescue ship with the location of the wreck.

In addition to the use of the buoyant container for valuables in the ship's vault or store room, I provide non-buoyant containers that are connected with the buoyant-container, and which may be lifted to the deck of the rescue ship by suitable hoisting apparatus, through the salvaging tube for the purpose of recovering their valuable contents.

The invention consists in certain novel combinations and arrangements of parts for accomplishing the purposes as here broadly stated, as will hereinafter be more fully set forth and claimed. In the accompanying drawings I have illustrated one complete example of the physical embodiment of my equipment in which the parts are combined and arranged according to one mode I have thus far devised for the practical application of the principles of my invention, but it will be understood that various changes and alterations may be made in the exemplifying structures, within the scope of my claims, without departing from the principles of my invention.

Figure 1 is a perspective view of a portion of a ship indicating by dotted lines the location of the salvaging equipment of my invention.

Figure 2 is a detail, longitudinal, vertical sec-

tional view of that portion of the ship in which is located the salvaging equipment, the salvaging tube and strong room of the ship being shown in section.

Figure 3 is an enlarged, detail sectional view showing the ship's vault, and the buoyant container in its normal position.

Figure 4 is an end view of a cable drum, forming part of the equipment, and illustrating a tension brake for the drum that controls the unreeling of the salvage cable.

Figure 5 is an enlarged detail sectional view of the closure or hatch at the upper end of the salvaging tube, and the operating means by which the hatch is released, and spring opened.

Figure 6 is a top plan view of the hatch closure of Fig. 5.

Figure 7 is a detail sectional view at the bottom of a modified form of salvaging tube, showing a portion of the buoyant container, and Figure 8 is a view showing three of the non-buoyant containers, one of which is illustrated as in section, and all connected in a "string" with the buoyant container.

In order that the general arrangement and location of parts of the equipment may readily be understood I have shown in Figure 1 a portion of a ship or ocean liner S with its several decks D and the top deck D' indicated in Figure 2. The strong room of vault V of the ship is provided with a suitable door V' and located in the usual position of the ship's structure. The salvaging tube T is preferably of cylindrical shape, built into the structure of the ship, and as indicated in Figure 2 the tube extends upwardly from the interior of the vault to and through the top deck D'. The lower end of the tube has a lateral adit opening 1 located within the vault, and the bottom of the tube is provided with openings A, A that are preferably tapered inwardly toward the interior of the tube, for circulation of air, and passage of water in the event that the ship sinks.

The upper end of the tube, above the upper deck D' is provided with a twin-hatch or closure 45 in the form of semi-circular doors 2 and 3 that are hinged at 4, exterior of the tube, and provided with overlapping free edges 5 to insure an inaccessible closure for the tube, and unauthorized tampering with the equipment.

The twin hatch doors 2 and 3 are each provided with vent holes 2', which, together with the vent holes A at the bottom of the tube, provide for ventilation of the tube, and also provide for escape of air from the tube, as well as provide for equali-

zation of water pressure in the tube when the vessel or ship becomes submerged.

The spring hatch doors are normally locked in closed position but when the lock is released the 5 twin hatch doors are swung upward and outwardly by springs 6 coiled about the hinges of the doors, as indicated by the dotted lines in Figure 5.

The twin hatch-doors are locked at their inner 10 sides by means of a slide bolt 7 extending transversely of the doors and mounted in straps or loops 8 fixed to the under surfaces of the two doors, and of course the bolt extends across the joint at the meeting edges of the doors. At one 15 end of the slide bolt a link 9 is pivoted, and this link is pivotally connected to one arm of a bell crank lever 10, which is pivoted at 11 in brackets of one of the doors. A weighted head 12, which is located at the center of the tube just below the 20 twin hatch doors, is pivoted at 13 to the longer arm of the bell crank lever, and this operating head is thus suspended in the path of movement of a buoyant container 14, which is designed to ascend through the tub, when the ship sinks 25 and water fills the submerged interior portion of the ship. The ascending buoyant container strikes the head 12 and lifts it, thereby swinging the bell crank lever and withdrawing the bolt from its locking position. The twin hatch doors 30 are thus released, and the springs 6 swing the doors open for the passage from the tube of the buoyant container, which latter rises to the surface of the water and performs the functions of a signal buoy for a rescue ship.

The buoyant container is fashioned from light 35 but strong material, and its cylindrical exterior is provided with suitable anti-friction devices, as balls or rollers 14' for contact with the interior of the cylindrical salvage tube to facilitate the ascending movement of the container as it passes up through the tube.

The container is formed with an inner shell 15 spaced within the outer shell, and reinforcing 45 partitions 16 between the shells provide air cells 17 that form a jacket surrounding the interior of the container. This jacket may contain air or light gas to insure the buoyance of the container in order that it will float to the surface of the water after leaving the salvage tube.

The top portion of the container is preferably 50 provided with a gas chamber 18 for confining a suitable lethal gas that is used as a precaution against possible tampering with the tube or with the container. Thus for instance, should burglary be attempted through the top of the container while it is confined in the bottom of the tube, the release of gas from this chamber would 55 be an effective means for preventing such operations.

The buoyant container is designed to contain 60 various valuables that may be stored therein during passage of the ship by the purser, and for this purpose the interior of the inner shell is provided with horizontal partitions 19 forming compartments 65 20, and doors 21, with the usual combination locks, are provided for each of the compartments, the doors being accessible through the adit opening 1 in the lower end of the tube, as indicated in Figure 3.

An audible signal, as a bell 22 is mounted on 70 the top of the buoyant container, to be sounded after the container reaches the surface of the water, by the rocking motion caused by waves, and a lifting frame or spider 23 is secured to the 75 top of the container, over the bell, and provided

with a ring 24, for attachment of a hoisting line or cable, when the container is hoisted aboard the rescue ship.

Under normal conditions the buoyant container rests in the bottom of the tube, within the strong room or vault of the ship, where it is readily accessible to authorized parties, as the purser or other officer of the ship, and the container is supported above the floor of the vault or strong room in such position as to insure freedom of movement of a 10 cable 25 that is attached to a ring 26 secured at the bottom of the buoyant container. This cable passes freely down through an eye 27 in the floor of the strong room, into a drum-chamber or compartment 28 beneath the strong room, and a drum 29 is mounted in this compartment with the cable wound thereon, the inner end of the cable, preferably, being loose from the drum. The cable of course is unwound from the drum when the buoyant container rises through the salvage tube, and the cable is hauled up through the tube and suspended from the buoyant container when the latter performs its functions as a signal buoy on the surface of the water.

The shaft 30 of the drum is journaled in bearings as 31, and the unreeling of the cable is preferably controlled by a tension brake which operates to retard paying out of the cable after the buoyant container has reached the water-surface. The tension brake applies a light frictional engagement of the brake shoes 32, hinged at 33, to the brake ring 34 that is mounted on the brake drum. These shoes encircle the brake ring as seen in Figure 4, and a tension bolt 35 is passed through holes in the two arms 36 of the shoes. 35 A tension spring 37 is coiled about the bolt and interposed between one of the arms and a nut 38 on the free end of the bolt, and it will be apparent that the spring will tend to close the two brake shoes or jaws 32 into frictional contact 40 with the brake ring. By adjusting the nut the tension of the spring may be varied and thereby the frictional contact of the brake members may also be varied for control of the rotary movement of the drum.

The container is made extremely buoyant by the use of light structural material having great strength, and the cells forming the jacket around the interior of the container may be exhausted of their air content to provide a vacuum, or the cells 50 may be filled with a buoyant gas, as is found desirable. The heavier articles are placed in the lower, water-tight, compartments of the container, and the lighter articles or valuables are placed in the upper compartments, to insure a 55 low center of gravity and upright position of the container when it floats on the surface of the water.

The buoyancy of the container is sufficient to 60 unreel and lift the cable as the buoyant container floats to the surface of the water, and should the depth from the surface to the bottom of the sea be greater than the length of the cable, the entire cable and its free inner end are unwound 65 from the drum and lifted free of the ship, the cable then serving to stable the movement of the buoyant container as it rides on the surface of the water, and to hold it in upright position. Should the container reach the water surface before the 70 entire cable is unwound, the tension brake on the drum provides an anchorage for the cable and the container, and the buoyant container indicates the location of the sunken ship to the rescue ship.

In the modified form of my invention illustrated in Figures 7 and 8, the use of the cable-drum is dispensed with, and the buoyant container and its salvage tube are utilized for salvaging other 5 and heavier valuable property in addition to the lighter articles stored in the container.

In Figure 7 it will be seen that the container, as 14', is supported adjacent the adit opening 1 of the tube, and just above an open, flaring end 10 39 of the tube. The container is supported in its normal position on displaceable trips 40 of angular shape, which are hinged at 41 in lugs 42 on the exterior of the tube, and the container is supported on the horizontal arm 40, while the upper 15 right arm of each trip is provided with a weight as 43. To support the container the trips are swung in through slots 44 of the tube-wall and the bottom of the container rests on these inwardly extending trips. When the container is lifted through the tube, as heretofore described, the trips are free to be turned on their hinges or pivots 41, and swung outside of the tube as indicated by the dotted lines in Figure 7.

The cable 45, which is connected to the container 14' is anchored to the first one, as 46, of three carriers, the other two being designated as 47 and 48. These carriers may be increased or decreased in numbers, and are designed in size and shape to pass freely through the inlet opening 39 of the tube, and thence up through the tube. The three carriers are connected by cables 49 and 50, and they are to be successively hauled up through the tube to the water surface, by suitable hoisting means on a salvage ship, after the location of the sunken ship has been signalled by the buoyant container 14' performing the functions of a signal.

The carriers are preferably cylindrical in shape and formed with one fixed head and a removable head, which are joined by means of a tie bolt, as indicated in the sectional carrier of Figure 8.

This tie-bolt 51 extends through the longitudinal axis of the carrier, and exterior of the carrier heads the bolt is provided with coupling rings 52 and 53 to which the cables, as 45 and 49 are connected, thus providing a "string" of carriers with intermediate cables connecting them through the tie-bolts of the carriers.

The fixed head of the cylindrical carrier has a countersunk portion 53' to accommodate the coupling ring 53, and the floor of the strong room or vault may be provided with a groove V2 to accommodate the cables 49 and 50, and thus permit storing of the carriers in suitable positions so that they may successively be picked up, lifted, and hoisted through the salvage tube T.

The removable head 54 of the carrier, which head is of circular shape, is countersunk below the top of the carrier to permit coiling of the pull cable or hoisting cable 45, 49, or 50, and the removable head is locked in closed position by means of a transversely extending bolt 55 having its ends secured in the wall of the carrier at opposite diametrical points. The underside of the removable head is fashioned with spaced eyes 56 and the locking bolt is passed through these eyes with its ends seated in the wall of the carrier, thereby securely fixing the head in the carrier.

The cable is coiled, as at 57 in the recess formed by the countersunk head within the carrier, and the formation of the coil is retained by the use of a flexible and resilient guard in the form of a disk 58 having a radial slot 59 to accommodate the cable, and formed with a central depressed cup 60 in which the eye or ring 52 of the tie bolt

is enclosed. The resilient and flexible guard 58, it will be understood, holds the coils of cables 49 and 50 in the recesses of the carriers 47 and 48, even though these carriers are shown as resting on their sides. Thus the coils of cables 49 and 50 are retained in position similar to the coil 57 in order that they, like the coil 57 may be unreeled without danger of tangling.

In Figures 7 and 8 it will be apparent that when the buoyant container 14' rises from its supports 10 and the cable 45 is uncoiled to its last turn, the strain will be imposed on the eye 52 of the tie bolt 51, and then the first carrier 46 will be in position to be hoisted by suitable machinery on a rescue or salvage ship to the water's surface. 15 The upper end of the cable 45 is detached from the salvaged buoyant container and this end is attached to and may be wound upon a hoisting drum. As the drum is turned the carrier is lifted through the flared guide-opening 39 at the bottom of the tube T, and as the carrier passes the trips 40 these devices are turned from the inner to the outer side of the tube, out of the way of succeeding carriers. As soon as the carrier 46 is started on its upward movement the coil of the 20 cable 49 starts unwinding from the carrier 47, and this carrier is eventually lifted from its resting place on the floor of the vault and passed upwardly through the salvage tube. Finally the last carrier of the "string" is lifted to the water's 25 surface and loaded onto the salvage ship.

These carriers are usually stored in a strong room or compartment of the ship directly below the ship's vault V, and the carriers are arranged in positions so that they may readily follow one 30 after another, up through the salvage tube during the salvaging operations.

While the buoyant container 14 is designed for storage of valuables of comparatively light weight, the carriers, on the other hand, are designed for storing heavier valuable cargo, such as specie, bullion bars, and other valuables that are heavy in weight, and are usually inaccessible during passage of the ship.

The buoyant-container, after its floats to the 45 surface of the water, provides a signal for the salvage or rescue ship, and the buoyant container is anchored by means of the carriers in the hold of the ship, it being understood that the cables 45, 49 and 50 are of sufficient length so that they 50 may extend from their respective carriers to the water's surface. Thus, after the ship is sunk, the first rescue ship may pick up the buoyant-container with its stored valuables, and replace the container with a suitable buoy attached at the 55 upper end of the cable 45. Then, when the salvage ship arrives, the buoy is picked up and detached from cable 45, the cable is wound upon hoisting mechanism to bring the carrier 46 to the surface. Carrier 46 is then disconnected from 60 cable 49 and the buoy attached at the upper end of this cable to hold the cable 49 until it can be attached to the windlass or winding drum on the salvage ship, and the same proceeding is carried out with respect to cables 49 and 50 and the carriers 47 and 48.

In this manner it will be apparent that valuables, documents, currency and the like may be recovered from a sunken or submerged ship or liner carrying my salvaging equipment, without 70 the necessity for the services of divers or the use of expensive salvage operations.

Having thus fully described my invention, what I claim as new and desire to secure by Letters Patent is:—

1. In salvaging equipment for a sunken ship, the combination with a buoyant container having a salvage cable attached thereto, of a carrier connected to said cable, said carrier having a countersunk head forming a recess for the coiled cable, and a coil-guard comprising a resilient flexible member overlapping the coil and means for securing said guard to the head.
- 5 2. In a salvaging equipment for a sunken ship, the combination with a buoyant container having a salvaging cable attached thereto, of a carrier having a countersunk head forming a recess for a coil of the cable, a coil-guard overlapping said coil, and means for securing said guard to said head.
- 10 3. In a salvaging equipment for a sunken ship, the combination with a buoyant receptacle having a salvaging cable attached thereto, of a pair of carriers, one of said carriers having a tie-bolt mounted therein and connected to an end of said cable, a second cable connected to said tie bolt and connected to the second carrier, each of said carriers having a countersunk head forming a recess for the coiled cable, a coil guard overlapping each of said coils, and means for securing said guard to a head.
- 15 4. In a carrier for salvaging equipment the combination with an open end receptacle, of a removable, countersunk head and means for se-

curing said head in the receptacle, a cable attached to the head, said cable being wound in a coil within the recess, a coil guard overlapping said coil, and means for securing said guard to the head.

5 5. In a carrier for salvaging equipment, the combination with a receptacle having a closed head and an open end, of a countersunk head having bolt eyes and a bolt passed through said eyes and secured in the wall of the receptacle, a tie bolt extending through said heads and a cable attached to said tie-bolt, said cable being wound in a coil in said recess, a resilient flexible guard overlapping said coil and provided with a slot for the cable, said guard having a central cup, 15 and a coupling eye on the tie bolt located in said cup for securing said guard.

6. In salvaging equipment, the combination with a salvage tube having a top closure confined within the tube and means for automatically 20 opening said closure, of a buoyant container, a pair of L-shaped supports pivoted exterior of the tube and projecting through holes in the tube for supporting the container, a cable connected to the container and a carrier fastened to the 25 cable, and said supports being gravity actuated to swing out of the tube when the buoyant container is floated.

ELISHA L. RADER.
